United States Patent Office

Des. 219,871

Patented Feb. 9, 1971

219,871

WHEEL

Thomas B. Griffith, San Carlos, Calif., assignor to American Racing Equipment, a corporation of California

Continuation-in-part of design applications Ser. No. 12,162, May 31, 1968, and Ser. No. 16,261, Mar. 17, 1969. This application July 24, 1969, Ser. No. 19,546

Term of patent 14 years

Int. Cl. D12—14

U.S. Cl. D14—30

Fig. 1

Fig. 2

Fig. 3

Fig. 4

FIG. 5.

FIG. 6.

FIG. 2

FIG. 8

FIG. 1 is a perspective view taken from the front and right side of a wheel showing one embodiment of my new design;

FIG. 2 is a front elevational view of the embodiment of FIG. 1;

FIG. 3 is a rear elevational view of the embodiment of FIG. 1;

FIG. 4 is a cross-sectional view taken along line 4—4 of FIG. 2;

FIG. 5 is a perspective view taken from the front and right side of a wheel showing another embodiment of my new design;

FIG. 6 is a front elevational view of the embodiment of FIG. 5;

FIG. 7 is a perspective view of the embodiment of FIG. 5 taken from the rear and right side; and

FIG. 8 is a rear elevational view of the embodiment of FIG. 5.

The hub covers and lug nuts shown in broken lines in FIGS. 5 and 6 are included for illustrative purposes only.

This application is a continuation-in-part of copending applications, Ser. No. D. 12,162, filed on May 31, 1968, and Ser. No. D. 16,261, filed on Mar. 17, 1969, both now abandoned.

I claim:

The ornamental design for a wheel, substantially as shown and described.
